[57] CLAIM

The ornamental design for a bootee, as shown.

DESCRIPTION

FIG. 1 represents a view of a silicone rubber substance called a "bootie", a static resistant cushion which covers a $1\frac{3}{8}$ " door knob to a 2" door knob, FIG. 1 slips over door knob to the dimensions of a total of 2" wide and $1\frac{1}{16}$ " thick to $\frac{1}{4}$ " thick and $1\frac{3}{8}$ " long;

The depth of the cushion is $\frac{1}{2}$ " deep with a $\frac{3}{8}$ " radius leading to the inside of the bootie, to the door knob lock, thusly the bootie serves as a cushion, preventing an indentation on any wall surface;

FIG. 2 illustrates the front view of the cushion. A basic $1\frac{3}{8}$ " opening with a width of 2" round;

FIG. 3 simply illustrates the cushion forming a cover over the standard door knob therefore becoming a round door knob. FIG. 3 is $2\frac{1}{4}$ " wide by $1\frac{3}{8}$ " long, the angled dimensions are $1\frac{1}{16}$ " to $\frac{1}{8}$ " thick. The front of cover is $\frac{1}{2}$ " in depth from the face of any standard door knob; and,

FIG. 4 illustrates the look of the "bootie" on the door knob at a front view, which is $2\frac{1}{4}$ " round.

FIG. 1

FIG. 2

FIG. 3

FIG. 4
